UNITED STATES PATENT OFFICE

GEORGE F. BROCKWAY, OF EDEN TOWNSHIP, FAYETTE COUNTY, IOWA.

METALLIC TIE.

1,136,771.

Specification of Letters Patent. Patented Apr. 20, 1915.

Application filed October 21, 1914. Serial No. 867,760.

To all whom it may concern:

Be it known that I, GEORGE F. BROCKWAY, a citizen of the United States, and a resident of Eden township, in the county of Fayette and State of Iowa, have made certain new and useful Improvements in Metallic Ties, of which the following is a specification.

This invention relates to improvements in metallic ties for railways, and more particularly to one of the hollow metallic shell type.

One object of the invention is to improve generally, and enhance the utility of a rail tie such as disclosed in my former Patent No. 1,103,652.

A further object is to so arrange and construct a hollow metallic tie that it will embody a minimum amount of material and at the same time possess the requisite rigidity and strength.

A further object is to provide a hollow metallic tie with internal bracing strips coacting with and anchored to a vertically arranged longitudinal web or truss bar so that the shell forming the body portion of the tie will be braced and made rigid in all directions, thus capable of withstanding those stresses and shocks to which it is subjected incident to its normal use.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed, without departing from the spirit of the invention.

In the drawings accompanying this specification and forming a part thereof, a preferable form of my invention is illustrated in which:

Figure 1 is a partial view in side elevation of my improved metallic tie. Fig. 2 is a sectional view taken on the line 2—2 of Fig. 1. Fig. 3 is a top plan view of the foregoing. Fig. 4 is a top plan view of the shell or body with the cover removed. Fig. 5 is a fragmental view of a side of the shell with the tongues in an unbent condition. Fig. 6 is a view in cross section illustrating a modified form of truss bar.

Referring to the drawings, in which similar reference numerals designate correspond-

ing parts throughout the several views, the tie includes a metallic body 6 formed with the bottom plate 7 and side walls 8. A top or cover plate 9 completes the hollow shell-like formation.

The top and bottom plates are provided with the longitudinal and outwardly extending ribs 10, which strengthen the shell and also define the internal grooves 11.

A truss bar 12 composed of one or more webs is positioned with its upper and lower edges within the internal rib defined grooves and braces the tie against vertical flexing or buckling. The side walls of the body are provided with spaced slots 14 arranged in pairs, so as to define a series of alternating wide and narrow tongues 15 and 16. The top plate is also provided with spaced slots defining a plurality of tongues 13 with the alternating tongues 13 fitting between and 75 coacting with the tongues 15 to hold and securely lock the cover and bottom portion in rigid relation and with the intermediate tongues 13 bent inwardly to define ledges upon which the tongues 15 rest and which 80 extend down against the side walls of the metallic body 6 and thus strengthen the entire structure.

The truss bar divides the hollow shell into two longitudinal compartments in which are 85 disposed the bracing strips 17, the same being formed of thin metal placed on edge and bent to form continuous and forwardly progressing loops of sinuous contour. The loops alternatingly contact with the side 90 walls of the body and centrally disposed truss bar to which latter they are rigidly secured by the rivets or allied means such as welding, etc., 19. The outer extremities of these distichous loops are securely anchored in place by the tongues 16, which are 95 bent thereover, as clearly illustrated in Fig. 2.

A U-bolt 24 extends through and is positioned substantially central of the tie, and 100 securely locks the cover plate to the tie body at this point, thus supplementing the holding action of the interlocking tongues. In order that the tie may successfully withstand the large local pressure at the extremities, 105 the bracing strips are thickened or doubled at these localities and above which the cushion blocks 27 and rail 28 are positioned. The rail and accessory clamping parts may partake of any desired form and are held se- 110

curely in place by means of the U-bolts 25, which pass through suitable apertures 26 provided in the tie.

The modified form illustrated in Fig. 6 5 includes the cross-shaped truss bar 12' which in addition to bracing the cover plate, adds materially to the transverse or lateral strength of the entire tie, coacting with the bracing strips 17 in this respect.

10 Having now fully described my invention what I claim is:—

1. A metallic tie comprising a body including side walls, a central web, and a sinuous bracing strip anchored to said web and 15 side wall.

2. A tie comprising a body including side walls, a longitudinal truss bar, and a sinuous bracing strip alternatingly contacting with and anchored to said truss bar and 20 body side walls.

3. A metallic tie comprising a body including side walls, a longitudinal centrally disposed truss bar disposed therein, and a sinuous bracing strip arranged on edge and 25 contacting at successive points with said truss bar and body side walls, and means anchoring the bracing strip at said points of contact.

4. A metallic tie comprising a shell with 30 longitudinal ribbed top and base plates, a truss bar anchored within and extending between the internal rib-defined grooves, and a continuous laterally bent bracing strip arranged on edge and alternatingly contacting with the shell side walls and said truss bar and anchored thereto at the points of 35 contact.

Copies of this patent may be obtained for five cents each, by addressing the "Commissioner of Patents, Washington, D. C."

5. A metallic tie comprising a body and cover plate with overlapping and interlocking tongues, said body and cover plate provided with outwardly projecting longitudinally extending ribs, a truss bar extending longitudinally of said body with the edges thereof disposed within the internal rib-defined grooves, sinuous bracing strips arranged upon opposite sides of said truss bar, secured thereto, and extending to the side walls of said body, said body provided with spaced tongues projecting over said bracing strips and locking the same in rigid relation with respect thereto.

6. A metallic tie comprising a hollow shell including body and cover plates with interlocking tongues, a vertical truss bar extending longitudinally of said shell and arranged centrally thereof, and distichous sinuous bracing strips with thickened end portions alternatingly contacting with and anchored to said truss bar and shell side walls.

7. A metallic tie comprising a hollow shell including interlocking body and cover plates, a vertical truss bar extending longitudinally of said shell and arranged centrally thereof and secured to said body and cover plates, 65 said truss bar provided with distichous forwardly projecting continuous loops anchored thereto contacting with the side walls of said body and held rigid with respect thereto.

GEORGE F. BROCKWAY.
